United States Patent Office

Des. 212,314
Patented Sept. 24, 1968

212,314

CLINICAL THERMOMETER HOLDER

Norma G. Walker, R.D. 1, Box 171,
Cortland, Ohio 44410

Filed Dec. 11, 1967, Ser. No. 9,743

Term of patent 14 years

(Cl. D83—1)

FIGURES 2, 3 and 4 are front, side and rear elevational views, respectively, of such holder.

I claim:
The ornamental design for a clinical thermometer holder, as shown.
